IRONING MACHINE

Andrew O. McCollum, Detroit, Mich., assignor
to Hydraulic Brake Company, Detroit, Mich.,
a corporation of California

Application November 12, 1934, Serial No. 752,730

10 Claims. (Cl. 38—41)

This invention relates to ironing machines, and more particularly to ironing machines for domestic use.

Broadly the invention comprehends an ironing machine having cooperative ironing elements including a stationary buck and an ironing head for cooperation with the buck, and hydraulically actuated means for moving the head against the buck to create an ironing pressure between the buck and the head.

An object of the invention is to provide an ironing machine including a buck, a head for cooperation with the buck, and hydraulically actuated means for moving the head against the buck.

Another object of the invention is to provide an ironing machine including a stationary buck, a head for cooperation with the buck, means supporting the head for movement into and from operative position, and hydraulically actuated means for applying force to the supporting means to create an ironing pressure between the buck and the head.

Other objects of the invention will appear from the following description taken in connection with the drawings which form a part of this specification, and in which,

Figure 1 is a side elevation, partly in section, of an ironing machine embodying the invention;

Figure 2 is a fragmentary view partly in section;

Figure 3 is a sectional view substantially on line 3—3, Figure 1;

Figure 4 is a sectional view of the actuating device;

Figure 5 is a top plan view of the actuating device;

Figure 6 is a fragmentary view illustrating a relief valve;

Figure 7 is a longitudinal sectional view of the relief valve;

Figure 8 is a diagrammatical illustration of the heating circuit.

Referring to the drawings for more specific details of the invention, 10 represents a frame having columns 12 and 14 arranged thereon in spaced relation and extending upward from the frame. The column 12 has at its top a spherical portion 16 and the column 14 has a reduced portion 18 providing a shoulder 20. The frame is supported in an elevated position by a column 22 and corresponding legs 24. The column 22 is suitably secured to the frame as by a sleeve 28 bolted or otherwise secured to the frame concentric to the column 12, and the respective legs are

bolted or otherwise secured to the respective sides of the frame.

A top 26 supported by the frame has an opening for the reception of the column 12 and a frusto-conical portion 30 having an opening in its top for the reception of the column 14. The top 26 also has an apron 32 which conceals from view the frame and the operating mechanism of the machine.

A fluid reservoir 34 suitably supported in the column 14 has therein a piston 36 provided with a concentric sleeve 38 extending through the head of the piston. The sleeve has thereon a circumferential flange 40, and a leak-proof cup 42 on the head of the piston is held against displacement by the flange. Threaded in the sleeve is a hollow piston rod 44 extended upward through a cover 46 suitably secured in the open end of the reservoir, and threaded in the outer end of the rod is a closure plug 48. A spring 50 interposed between the back of the piston and the cover 46 urges the piston toward the bottom of the reservoir. By removing the plug 48 and retracting the piston, the reservoir 34 may be filled through the hollow rod 44.

A buck 52, which may be of any conventional type, has a dependent sleeve 54 receiving the reduced portion 18 on the sleeve 14 and abutting the shoulder 20. A key 56 locks the sleeve 54 to the sleeve 14 to retain the sleeve 54 against rotation. By removing the buck 52, access may be had to the reservoir 34.

An arm 58 has a portion formed as at 60 for the reception of the spherical portion 16 on the column 12 and an internal web 62 supporting an extension 64. This extension protrudes downward into the column 12 and is pivotally connected to the spherical portion 16 by a pintle 66. A yoke 68 pivoted to the arm 64 is connected by a spring 70 to an adjustable member 72 on a fixed support 74 on the frame. This spring serves to return the arm 58 to its normal or elevated position upon the completion of each operation of the machine.

The other end of the arm 58 has oppositely disposed corresponding arms 76 to which is pivotally connected an ironing head 78 for cooperation with the buck 52, and suitably connected to the arm 58 between the arms is a rod 80 on the free end of which is a hand grip 82 by which the arm 58 may be actuated to move the head into operative position.

A stub shaft 84 is mounted on the frame, and a bushing 86 is mounted on the frame coaxial to the shaft. An operating shaft 88 is journaled 55

in the bushing. The stub shaft and the bushing support a fluid pressure device to be hereinafter described. The operating shaft 88 has suitably secured thereto an operative lever 90 to which an extension 92 is adjustably attached, and the extension is provided with a hand grip 94. The operating shaft also has suitably secured thereto a cross arm 96 provided at one end with a laterally extending arm 98 carrying an adjustable abutment screw 100.

5 The fluid pressure device includes a cylinder 102 having co-extensive spaced parallel arms 104 and 106. The arm 104 has a sleeve 108 receiving the stub shaft 84, and the arm 106 has a sleeve 110 receiving the sleeve 86, and the sleeve 110 has an arm 112 connected by a spring 114 to a fixed support on the frame. The cylinder has an intake port 116 connected by a flexible tube 118 to the reservoir 34 as indicated at 120, and 15 a discharge port 122 communicating with a chamber 124, and the port 122 is controlled by a check valve 126.

20 The chamber 124 has an opening 130 in which is threaded a fluid pressure switch 132 connected in a circuit 134 including a lamp 136. The circuit 134 is tapped off of a circuit 138 including a heating element 140 suitably arranged in the head 78 and a rheostat 142 on the head for controlling the circuit.

25 30 A cylinder 144 arranged in a plane parallel to the axis of the cylinder 102 and integral with the cylinder 102 has a port 146 providing a communication between the cylinder 144 and the valve chamber 124. The cylinder 144 has formed thereon a boss 148 provided with a flat surface 150 adaptable for cooperation with a flat surface 152 on the interior of the sleeve 12, and formed on the wall of the cylinder 144 diametrically disposed to the boss 148 is a cylinder 154 having a port 156 providing a communication between the cylinder 154 and the cylinder 102, and formed on the cylinder 144 is an arcuate track or runway 158 on which the free end of the arm 64 travels.

35 40 A reciprocatory piston 160 in the cylinder 102 has a reduced body portion providing in conjunction with the wall of the cylinder an annular chamber 162 communicating with the intake port 116, and a plurality of ports 164 in the head of the piston provide communications between the annular chamber 162 and that portion of the cylinder 102 forward of the head. A leak-proof cup 166 on the head of the piston controls the ports 164, and a relatively light spring 168 interposed between the cup 166 and the head of the cylinder 102 retains the cup against displacement and serves to return the piston to its retracted position. The skirt of the piston has a circumferential groove 170 in which is fitted a leak-proof packing member 172, and formed in the back of the piston is a recess 174 for the reception of one end of a thrust rod 176, the other end of which is pivotally connected to the arm 96.

45 50 A reciprocatory piston 178 in the cylinder 154 has on its head a leak-proof cup 180, and formed on the back of this piston is a short stout plunger 182 extending through an opening in the head 184 threaded in the cylinder. This plunger is adaptable for cooperation with a flat surface 186 on the interior of the sleeve 12, and interposed between the piston and the head 182 is a spring 188 for returning the piston to its retracted position.

55 60 A reciprocatory piston 190 in the cylinder 144 has on its head a leak-proof cup 192, and suitably secured to the back of this piston is a plunger

65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

194 having a reduced portion 196. The piston is normally held in retracted position by a spring 198 interposed between the back of the piston and suitable stops 200 threaded in the wall of the cylinder. The free end of the plunger is bevelled as indicated at 202 for cooperation with the extension 64 of the arm 58. The beveled face 202 on the free end of the plunger 196 has a variable engagement with the arm dependent upon the thickness of the work between the buck and the head.

199 204 209 214 218 220 224 226 228 232 234 244 254 264 274 284 294 304 314 324 334 344 354 364 374 384 394 404 414 424 434 444 454 464 474 484 494 504 514 524 534 544 554 564 574 584 594 604 614 624 634 644 654 664 674 684 694 704 714 724 734 744 754 764 774 784 794 804 814 824 834 844 854 864 874 884 894 904 914 924 934 944 954 964 974 984 994 1004

A valve chamber 204 formed on the wall of the cylinder 102 has a port 206 and a passage 208 connecting this port to the intake port 116. This valve chamber also has a port 210 connected by 15 a passage 212 to a port 214 in the chamber 124. A valve cage 216, suitably secured in position as by a plug 218 threaded in the open end of the chamber 204, has a valve seat 220 positioned intermediate the ports 206 and 210, and a reciprocal 20 valve 222 arranged for cooperation with the seat 220 has a rod 224 extending through the head of the chamber. Sleeved on the rod 224 are leak-proof cups 226 and 228 held in position by a spring 230. Also sleeved on the rod between the 25 head of the chamber and a stop 232 on the rod is a spring 234 urging the valve to its seat.

Assuming that the fluid pressure system is filled with fluid, that the circuit 138 is connected to a suitable source of electrical supply and that 30 the ironing head 78 is in elevated position,—under these conditions, the operator places the work upon the buck and manually lowers the head 78 into operative position, which position varies according to the thickness of the work.

35 In moving the head into operative position, the springs 70 are placed under tension and the free end of the arm 64 travels over the track 158. When the arm 64 clears the track 158, the spring 194 becomes effective to swing the fluid pressure 40 device so that the bevelled end 202 of the plunger 194 engages the extension 64 of the arm 58 and retains the arm against movement. Because of the variable engagement between the arm 64 and the plunger 194, the arm 64 and hence the ironing head 78 supported thereby may be retained in any one of a number of operative positions.

45 After moving the head into operative position, the operator manually actuates the lever 90 by pressing downward on the hand grip 94. This 50 movement of the lever 90 rocks the shaft 88 with the result that the arm 96 secured to the shaft is moved through an angle, and this movement of the arm 96 is transmitted through the thrust pin 176 to the piston, resulting in moving the 55 piston on its compression stroke.

Upon movement of the piston 160 on its compression stroke, fluid is displaced from the cylinder 102 past the check valve 126 into the chamber 124, thence through port 146 into cylinder 60 144, and thence through port 156 into cylinder 154, resulting in moving the piston 190 in the cylinder 144 and the piston 182 in the cylinder 154 on their compression strokes. The piston 182 is moved to engage a flat 186 on the interior 65 of the column 12 with sufficient pressure to retain the fluid pressure device against movement, and the piston 190 is moved against the arm 64. This movement of the piston 190 is transmitted through the arm 64, the arm 58 integral therewith, and the horns 76 on the arm 58 to the head 78, resulting in moving the head 78 against the buck 52 and creating an ironing pressure between the head and the buck.

70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Upon maintaining the pressure for a sufficient 75

period of time to effectively iron the work, the operator lifts the lever 90. This movement of the lever 90 rocks the shaft 88 in the reverse direction and moves the arm 96 secured thereto through an angle, and this movement of the arm 96 is transmitted to the thrust pin 176, resulting in retracting the thrust pin from the piston 160.

As the thrust pin moves to its retracted position, the piston 160 also moves to its retracted position under the influence of the return spring 168. During the movement of the piston 160 to its retracted position, the cup 166 on the head of the piston collapses and fluid is drawn from the reservoir 34 through the conduit 118 and port 116 into the chamber 162, thence through ports 164 in the head of the piston 160, past the cup 166 into the cylinder 102 forward of the piston, completely filling the cylinder for a subsequent operation.

Upon further movement of the operating lever 90 in the reverse direction, the driver 98 on the arm 96 is moved with force against the stem 224 of the valve 222, resulting in tripping the valve. Upon tripping the valve 222 the pressure on the fluid in the cylinders 144 and 154 is released, and the fluid in these cylinders is returned under the influence of the springs 198 and 118 acting on the respective pistons 190 and 182.

The fluid returns from the cylinder 154 to the cylinder 144, and thence through the port 146, valve chamber 124, port 214, passage 212 and port 210 into the valve chamber 204, past the valve 222, and through port 206, passage 208 and conduit 118 to the reservoir.

Upon retraction of the piston 182 the pressure retaining the fluid pressure device against movement is released, and upon retraction of the piston 190 the applied force on the arm 64 is released. With these pressures released, the force applied on the valve stem 224 moves the fluid pressure device to the position of rest, in which position the extension 64 of the arm 58 is released, whereupon the springs 70 become effective to return the head 78 to elevated position.

It is to be understood that the form of the invention herein shown and described is to be taken as a preferred example, and that various changes in shape, size, and arrangement of parts may be resorted to without departing from the spirit of the invention or scope of the subjoined claims.

Having thus described the various features of the invention, what I claim as new and desire to secure by Letters Patent is,—

1. An ironing machine comprising a stationary buck, a head for cooperation with the buck, a pivoted arm supporting the head for movement into and from operative position, manually operative means for moving the head into operative position, a fluid pressure device, means for automatically moving the device bodily into engagement with the arm upon movement of the head into operative position, manual means for actuating the device to apply force to the arm for moving the head into pressing engagement with the buck, means operated by the actuating means for releasing the applied force and disengaging the device from the arm, and means effective upon disengaging the device from the arm to return the head to inoperative position.

2. An ironing machine comprising a stationary buck, an arm pivoted between its ends, a head supported on one end of the arm for cooperation with the buck, manual means for actuating the arm to move the head into operative position,

means tending to move the head from operative position, a fluid pressure device, means for automatically moving the device bodily into engagement with the arm upon movement of the head into operative position, manually operative means for actuating the device to rock the arm and thereby move the head into pressing engagement with the buck, means actuated by the manual means for releasing pressure in the pressure producing device and for moving the device out of engagement with the arm and means effective for moving the head to inoperative position upon disengaging the device from the arm.

3. An ironing machine comprising a stationary buck, an arm pivoted between its ends, a head on one end of the arm for cooperation with the buck, manual means for actuating the arm to move the head into operative position, means tending to move the head from operative position, a fluid pressure device including a pump and a motor actuated thereby, means automatically effective upon movement of the head into operative position to move the device bodily to engage the motor with the other end of the arm, and means for actuating the pump to move the head into pressing engagement with the buck.

4. An ironing machine comprising a frame, a stationary buck on the frame, an arm pivoted on the frame, a head on the arm for cooperation with the buck, a fluid pressure device on the frame movable for engagement with the arm including a pair of fluid pressure actuated pistons, one for engaging the frame to retain the device in a fixed position and the other for engaging the arm to move the head into pressing engagement with the buck, and a pump for actuating the pistons.

5. An ironing machine comprising a frame, a stationary buck on the frame, a member pivoted to the frame, a head on the member for cooperation with the buck, a device pivoted on the frame for actuating the member to move the head into pressing engagement with the buck, said device including fluid pressure actuated motors and a pump for actuating the motors, means for moving the device bodily to engage the piston of one of the motors with the member and the piston of the other motor with the frame, means for actuating the pump, and means actuated by the operating means for releasing the pistons of the motors and moving the device out of engagement with the arm after completing the ironing operation.

6. An ironing machine comprising a stationary buck, a head for cooperation with the buck, a pivoted arm supporting the head for movement into and from operative position, a fluid pressure device mounted to swing bodily into and out of engagement with the arm, means for automatically moving the fluid pressure device into engagement with the arm upon movement of the head into operative position, manually operative means for actuating the fluid pressure device to move the head into pressing engagement, and means actuated by the manually operative means for moving the device out of engagement with the arm upon completing the pressing operation.

7. An ironing machine comprising a stationary buck, a head for cooperation with the buck, a pivoted arm supporting the head for movement into and from operative position, manually operative means for moving the head into operative position, means tending to move the head from operative position, a fluid pressure device mounted to move bodily into and out of engage-

- ment with the arm, means effective to automatically move the fluid pressure device into engagement with the arm upon movement of the head into operative position, manually operative means for actuating the fluid pressure device to move the head into pressing engagement with the buck, and means actuated by the manually operated means for moving the fluid pressure device from engagement with the arm upon completion of the 10 pressing operation.
8. An ironing machine comprising a frame, a stationary buck on the frame, an arm pivoted on the frame, a head on the arm for cooperation with the buck, manually operative means for 15 moving the head into operative position, means cooperating with the arm for moving the head from operative position, a fluid pressure device including a pair of fluid pressure motors, a pump for actuating the motors and a relief valve for the motors, means for moving the fluid pressure device to engage the piston of one of the motors with the arm and the piston of the other motor with the frame, manual means for operating the pump to retain the device against movement and to actuate the head into pressing engagement with the buck, and means for tripping the valve and for moving the fluid pressure device to its position of rest upon completion of the pressing 19 operation.
10. In an ironing machine, a stationary buck, a movable head, a pivoted arm supporting the head for movement into and from operative position, a fluid pressure device mounted to swing 20 into and from the path of movement of the arm including fluid pressure actuated means for retaining the device in the path of movement of the arm, means for automatically swinging the device into the path of movement of the arm 25 upon movement of the head into operative position, means for operating the device to transmit force through the arm to the head to actuate the head into pressing engagement with the buck, means for releasing pressure in the fluid pressure 30 device, and means for moving the fluid pressure device from the path of movement of the arm upon completion of the pressing operation.
9. An ironing machine comprising a frame, a stationary buck on the frame, an arm pivoted on the frame, a head on the arm for cooperation

ANDREW O. McCOLLUM.
